[57] CLAIM

The ornamental design for a table, substantially as
shown and described.

DESCRIPTION

FIG. 1 is a perspective view of a table showing my new
design;

FIG. 2 is a side elevation view thereof;

FIG. 3 is a top plan view thereof;

FIG. 4 is a bottom plan view thereof;

FIG. 5 is a right end view thereof;

FIG. 6 is an enlarged fragmentary perspective view of
a corner thereof;

FIG. 7 is a front perspective view of another embodiment
thereof;

The side opposite FIG. 2 is a mirror image thereof. The
end opposite FIG. 5 is a mirror image thereof.
